JOHN GALVIN, OF BROOKLYN, NEW YORK.

METAL-SHAVING MACHINE.

Application filed February 21, 1924. Serial No. 694,217.

My present invention relates more particularly to shaving wire with grooved knives to produce steel wool, but it will be obvious that certain of its features may prove useful for shaving material other than wire as, for instance, metal bands, to produce a product other than steel wool.

As concerns my specific purpose of producing steel wool, the general objects of the invention are to decrease the amount of floor space required for each machine, to increase the number of shaving knives that can be used in each machine and to otherwise improve and cheapen the cost of production.

In the present-day commercial art, steel wool is made by machines wherein there is a stationary bed formed with a grooved support for the wire along which the wire is dragged from a supply reel at one end, to a drawing reel at the other end. There are a number of shaving knives rigidly but adjustably supported in operative relation to the wire that is dragged along the groove. There is reversing mechanism whereby the reels are reversed at the end of each pass, so that the wire is dragged alternately in opposite directions until completely used up by the shaving knives. The number of knives is limited to a great extent by the friction of the wire as it is dragged over the stationary bed under pressure of the knives and in actual practice six or eight, or at most ten, knives are all that can be used. This is because economy requires shaving the wire down to the smallest permissible cross-section and if there are too many knives, the traction required to drag the wire beneath them will become too great and the wire will break before it has been shaved down to economical thinness.

It has been proposed to use a rotating grooved support for the wire as a substitute for the stationary bed, but my invention contemplates a novel arrangement of the rotating support and also improved means whereby the direction of the traction on the wire may be reversed and the direction of the shaving knives reversed; all in addition to the other objects above referred to.

All of these various purposes and the means whereby they are accomplished may

be more fully understood from the following description in connection with the accompanying drawings, in which—

Figs. 1 and 2 are respectively edge view and side elevation indicating the general organization of the machine, the details of which are further illustrated in the remaining figures;

Fig. 3 is a plan view of the reversing mechanism taken on the line 3, 3, Fig. 2;

Fig. 4 is a detail view on an enlarged scale showing one of the wire supports and the shaving knife in operative relation thereto, the same being one of the shaving units as diagrammatically indicated in Fig. 1;

Fig. 5 shows the same parts viewed from the bottom of Fig. 4 and from the left of Fig. 6;

Fig. 6 is a vertical section on the line 6, 6, Fig. 5;

Fig. 7 is a detail plan view of spline locking and releasing mechanism shown in Fig. 1;

Fig. 8 is a section on the line 8, 8, Fig. 7, showing the spline in the locked position;

Fig. 9 is a similar section showing the spline in the unlocked position;

Fig. 10 is an enlarged fragmentary section through the work support, showing the relation of the shaving knife to the latter.

The machine comprises a base, 1, having standards, 2, 2, in which the supply and drawing reels and the reversing traction means therefor are mounted. The upper ends of supports 2 carry a platform member, 5, secured thereto by bolts, 6, 6, and said platform has rigidly secured thereto by bolts, 7, 7, the upright frame members, 8, 9, spaced apart and rigidly braced at the top by transverse members, 10 and 11, secured by bolts 12. The lower member carries the lower half 13 and the upper member the upper half 14 of a bearing for wheel 16.

The uprights 8, 9, carry the two sets of wheels 20, 20, rotatably mounted on stud shafts 21, 21. The outer edges of supports 8, 9, carry the supports 30, 30, for knives 31, 31. The wire *w* is drawn from supply reel 60 and brought into exact alignment with the periphery of one set of wheels 20 by means of a guide roller 20^a. Thence it passes upward along the aligned peripheries

of wheels 20 and beneath the knives 31 to the periphery of the large diameter wheel 16 at the top of the machine. The latter is an anti-friction means for changing the direction of the wire and bringing it into exact alignment with the peripheries of anti-friction wheels 20 on the other side of the machine. On this side the knives 31 are directed upwardly so as to be in the same relation to the wire as are the knives 31 on the up-side of the machine. From the last roller 20 the wire passes under another guide roller 20^b and thence to the drawing reel 80.

As before explained, the direction of drive is reversed at the end of each pass of the wire, the original supply reel 60 becoming the drawing reel and the reel 80 becoming the supply reel. This of course requires reversal of the direction of the knives whenever the direction of draft of the wire is reversed. The draft reversing mechanism and the knife reversing and adjusting mechanisms will now be explained in connection with the detail views.

By reference to Figs. 4, 5 and 6, it will be seen that the knife holder 30 is a box-like structure swiveled on base plate 30^a, which is secured by screws 32, on supporting block 33, which is transversely slidable in a dovetail recess 34 in the upright 8 (or 9, as the case may be). The dovetail slide 33 extends in a direction parallel with the edge of the knife 31, so that successive sharper portions of the edge may be adjusted into engagement with the wire *w*, when the portions in use have become dull. The transverse adjustment is controlled by screw 35 engaging screw lug 36 on the slide 33. The screw 35 is prevented from endwise movement by swivel collar 37 and is operated by handle 38. The knife 31 is clamped in a tool holder 39 by screw 40. The tool holder is rotatably held in box 30 by flange-headed screws 41, 41. The adjustment of the knife is gauged by a tail set screw 42 against which it is held in firm engagement by spring 43 encircling screw 44 which serves as means for anchoring said spring. The other end of the spring engages a stud 45 on the knife blade 31.

The entire tool holding box 30 pivots on screw 46, which is rigidly screwed into base 30^a. When the direction of draft of the wire is reversed, the knife is reversed by pivoting about said screw 46. In either position it is held by bolt 48, spring pressed downward by spring 49 and having a head 50 by which it may be retracted. In Figs. 4 and 6 the locking bolt hole not in use is marked 48^a. In actual practice, the size of the tool holder, the position of its pivot and the sizes of the rollers 20, 20, are such that in one position the knife edge will rest on one roll at the end of its horizontal di-

ameter and when reversed it will rest on the next roll at the end of its horizontal diameter.

As appears more clearly in Fig. 3, the reel 60, which is serving as a supply reel, is mounted on shaft 61 and the reel 80, which is serving as a drawing reel, is mounted on a similar shaft 81. Each reel is longitudinally slidable on its shaft and has means whereby it may be splined for rotation with its shaft, as shown in Fig. 8, or may be unsplined for free rotation, as shown in Fig. 9. The engagement or release of the spline may be effected by hand or in any other desired way. As shown in Fig. 8, the shaft 81 has a spline groove 82, in which is engaged spline 83 carried by an operating shank 84, by which it may be retracted and turned to the position shown in Fig. 9. Preferably, there is a detent 85, which fits a locking recess 86 when the spline is in groove 82, and which is turned crosswise of said recess when said spline is retracted to hold it in the retracted position, as indicated in Fig. 9.

As indicated by the arrows in Fig. 3, shafts 61 and 81 are rotated in the same directions by means of gears 61^a, 81^a, engaging gear 90 on the main drive shaft 91. When it is desired to stop or reverse the direction of rotation of the reels, the shaft 91 will be stopped or reversed. Consequently, when reel 80 is splined to shaft 81, as shown in the drawings, the direction of rotation is such that the reel is being power rotated to wind up the wire. At this time the supply reel 60 is free to rotate, opposed only by friction. When reel 80 is unsplined and 60 is splined, the direction of rotation is reversed so that reel 60 becomes the power drawing reel and 80 the supply reel.

As the end tension on the wire is always great, it is necessary to provide level winding means whereby the reels are reciprocated axially to lay the wire in smooth layers and to keep the winding point exactly in the plane of the grooves in the peripheries of wheels 20. In the arrangement shown, the reels are simultaneously reciprocated through flange collars 62, which are rigid with the respective reels. Behind these collars are engaged lugs 63, carried by arms 64 projecting endwise from a sleeve 65 having a cam slot 66 engaged by stationary camming pin 67 secured to the frame by suitable support 68, so that rotation of the cam sleeve necessarily cams it endwise of the shaft. The cam slots 66 of the respective cam sleeves 65 are arranged in like phase and are rotated by gears 68 slidably engaging along pinions 69 on shafts 92 both driven by gear 94 on shaft 91. It will be understood that the gear train 94, 93, 69, 68, is a reducing-gear train of such ratio that the reels 60 and 80 will be rotated

enough times to lay down and level wind a complete layer of wire during the time that the sleeve 65 is being rotated a half revolution. Such half revolution will cause the cam slot 66 to complete a one direction camming of the sleeve and attached drum in one direction, while a continuation of the slot will similarly complete a traverse in the other direction during the next half revolution.

From the above the operation of the device will be evident. One of the reels, as 60, is provided with a coil of wire of any desired length. The wire is threaded into the machine, in the grooves in the support rolls 20 and under knives 31 and over the large pulley 16 at the top; thence down in the grooves of the second set of rolls 20 under its set of knives 31; thence by guide pulley 20^b to the reel 80, to which it is secured in any desired way. The reel 80 is then splined to its shaft 81 and the supply reel 60 is unsplined on its shaft. The drive shaft 91 being then started, the machine will operate until, when the wire on the supply reel is nearly run out, shaft 91 will be stopped, the spline engagements will be reversed, the locking bolts 48 will be retracted, the knife holders 30 will be rotated upon pivots 46, through an angle of 180 degrees to bring the edge of the cutting knife into registry with the periphery of the next adjacent support roll 20, and, finally the shaft 91 will be re-started in the reverse direction, thus making reel 60 the drawing reel.

The steel wool shaved by the knives 31 may be removed in any desired way, preferably by means of air jets directed through nozzles 100, 100, supplied with compressed air through pipes 101, 102, 103, 104, 105, supplied by a centrifugal blower 106 of any desired type, rotated from any suitable source of power as by belt 107. The wool driven off by the air blast may be collected, as by a hood 108, leading to chute 109, shown in dotted lines in Fig. 1.

It will be understood that the knives will be renewed and adjusted from time to time as may become necessary.

50 I claim:—

1. A machine for making steel wool, a base frame supporting supply and drawing reels and means for rotating and causing traverse of the same, in combination with an upright support located on the base support and embodying two vertically extending series of knives and cooperating supports for the wire and, at the top, an anti-friction wheel having its periphery in alignment with both sets of knives.

2. A machine for making steel wool, a base frame supporting supply and drawing reels and means for rotating and causing traverse of the same, in combination with an upright support located on the base sup-

port and embodying parallel uprights carrying a series of grooved, aligned anti-friction rollers, each series serving as a bed for the wire and cooperating grooving knives, one for each roll.

3. A machine for making steel wool, a base frame supporting supply and drawing reels and means for rotating and causing traverse of the same, in combination with an upright support located on the base support and embodying parallel uprights carrying a series of grooved, aligned anti-friction rollers, each series serving as a bed for the wire and cooperating grooving knives, one for each roll and, at the top, an anti-friction wheel having its periphery in alignment with both sets of knives.

4. A machine for making steel wool, a base frame supporting supply and drawing reels and means for rotating and causing traverse of the same, in combination with an upright support located on the base support and embodying parallel uprights carrying a series of grooved, aligned anti-friction rollers, each series serving as a bed for the wire and cooperating grooving knives, one for each roll, said knives being each mounted in a swiveled support with its cutting edge opposite the vertical portion of the periphery of one of the rolls, and the parts being proportioned so that when the supports are reversed each knife is presented in the same operative relation to the vertical portion of the periphery of the next adjacent roller.

5. A machine for making steel wool, a base frame supporting supply and drawing reels and means for rotating and causing traverse of the same, in combination with an upright support located on the base support and embodying parallel uprights carrying a series of grooved, aligned anti-friction rollers, each series serving as a bed for the wire and cooperating grooving knives, one for each roll and, at the top, an anti-friction wheel having its periphery in alignment with both sets of knives, said knives being each mounted in a swiveled support with its cutting edge opposite the vertical portion of the periphery of one of the rolls, and the parts being proportioned so that when the supports are reversed each knife is presented in the same operative relation to the vertical portion of the periphery of the next adjacent roller.

6. A base frame and an upright steel wool machine supported thereby including two vertical beds, an anti-friction direction changing means above and between the beds for guiding stock from one bed to the other, the base frame containing supply reel and a drawing reel operating on the same length of wire, arranged closely adjacent each other and geared to a single drive shaft located between them.

7. A base frame and an upright steel wool machine supported thereby, including two vertical beds, an anti-friction roller supporting above the bed for guiding stock from one bed to the other, the base frame containing supply reel and a drawing reel operating on the same length of wire, arranged closely adjacent each other and geared to a single drive shaft located between them, each reel having means whereby they may be reciprocally, one splined and the other unsplined to their supporting shafts.

8. A machine for making steel wool, comprising a base frame containing supply and drawing reels mounted on parallel shafts geared to a single drive shaft located between them, said reels having means whereby they may be reciprocally, one splined and the other unsplined to their supporting shafts, in combination with an upright support located on the base support and embodying parallel uprights carrying a series of grooved, aligned anti-friction rollers, each series serving as a bed for the wire and cooperating grooving knives, one for each roll and, at the top, an anti-friction wheel having its periphery in alignment with both sets of knives; said knives being each mounted in a pivotal support and the parts being proportioned so that when the supports are reversed each knife is presented in operative relation to the next adjacent roller.

9. A steel wool machine including a pair of parallel vertically disposed beds, means for drawing wire up over one bed then across to and down over the other bed, a plurality of cutting knives arranged adjacent the beds for operating upon the wire passing thereover, means for reversing the direction of movement of the wire, and means for reversing the position of the cutting knives.

10. A steel wool machine including a pair of parallel vertically disposed beds and means for drawing wire up over one bed then across to and down over the other bed, a plurality of cutting knives arranged adjacent the beds for operating upon the wire passing thereover, means for reversing the direction of movement of the wire, and means for reversing the position of the cutting knives, each of said beds including vertically disposed series of aligned rolls having wire guiding grooves in their periphery.

11. A steel wool machine including a pair of parallel vertically disposed beds, means for drawing wire up over one bed then across to and down over the other bed, a plurality of cutting knives arranged adjacent the beds for operating upon the wire passing thereover, means for reversing the direction of movement of the wire, and means for reversing the position of the cutting knives, each of said beds including vertically disposed series of aligned rolls having wire cutting grooves in their periphery, and a direction changing means above the beds for guiding the wire from one to the other.

12. In a steel wool machine, a base frame including a supply reel and a traction reel for the same length of wire, located closely adjacent one another, a pair of parallel vertically disposed beds with intermediate means for guiding the wire from one bed to the other arranged above the base frame over which wire from the supply reel is adapted to be drawn by the traction reel and vertically disposed series of knives arranged to shave the wire as it passes upwardly across one bed and downwardly across the other.

Signed at New York, in the county of New York and State of New York, this 20th day of February, A. D. 1924.

JOHN GALVIN.
